UNITED STATES PATENT OFFICE.

A. B. NIMBS, OF BUFFALO, NEW YORK.

IMPROVEMENT IN COAL-ELEVATOR BUCKETS.

Specification forming part of Letters Patent No. 44,108, dated September 6, 1864.

To all whom it may concern:

Be it known that I, ARHEUNA B. NIMBS, of the city of Buffalo, county of Erie, and State of New York, have invented a new and Improved Coal-Elevator Bucket; and I do hereby declare that the following is a full and exact description thereof, reference being had to the accompanying drawings, making a part of this specification, in which—

Figure I is a top plan; Fig. II, a transverse section; and Fig. III, a front elevation.

Letters of like name and kind refer to like parts in each of the figures.

The nature of this invention consists, first, in protecting and strengthening a sheet-metal elevator-bucket of common form by means of wrought-iron bars or ribs placed vertically upon the outside of the bucket equidistant from each other, and welded or otherwise connected to a horizontal bar at the back of the bucket, by which bar the bucket is hung or connected to the carrying belt or chain; second, in prolonging the strengthening bars so that they will project upward above the dipping edge of the bucket, and form prongs or fingers which aid and greatly facilitate the filling of the buckets.

A represents the sheet-metal bucket of common form and to which the strengthening-bars are connected.

B B represent the strengthening and protecting bars or ribs, welded or otherwise fastened at equal distances (or nearly so) from each other to the back bar, C, and to the main body of the bucket. These bars are bent to the form of a vertical section of the bucket,

which is fastened to them by riveting or otherwise. They give great stiffness and strength to the bucket, and protect it from bruising when dipping into the coal. They also project upward beyond the dipping-edge of the bucket, forming prongs or fingers, as shown at b'. These prongs not only protect the edge of the bucket from injury, but cause it to enter the coal easily and fill itself without straining. Without them it would be impossible to fill the bucket when the lumps of coal were of any considerable size, and the dipping-edge would soon become so battered and cut as to render the bucket worthless; but the prongs, striking easily into the interstices between the lumps, gather them into the bucket without shock or strain.

C represents a wrought iron bar placed horizontally across the back edge of the bucket to strengthen the same, and to which the rear ends of the bars B are connected, as before described.

What I claim as my invention, and desire to secure by Letters Patent, is—

1. A coal-elevating bucket having vertical strengthening-bars B and a horizontal back bar, C, substantially as described.

2. Prolonging the strengthening-bars B so that they will project upward above the main body of the bucket, as shown at b', substantially as set forth.

A. B. NIMBS.
